UNITED STATES PATENT OFFICE

GEORGE L. NOLETTE, OF WORCESTER, MASSACHUSETTS, ASSIGNOR OF ONE-HALF TO
ABRAHAM NOLETTE, JR., OF WORCESTER, MASSACHUSETTS

JACK

Application filed February 3, 1928. Serial No. 251,547.

This invention relates to improvements in jacks. More especially it relates to jacks for vehicles and the like, embodying features which have been designed with particular regard to requirements of jacks suitable for handling automobiles equipped with "balloon" tires. The invention presents structural and operative novelty in jacks, whereby, as compared with usual constructions, a greater range of extensibility in a given size of jack may be provided; and a material increase in the speed of operative adjustment.

Jacks suitable for handling automobiles equipped, as is the present day custom, with the comparatively new "balloon" type of tires have to be contractible to a height which permits of their insertion under a fallen axle, e. g. under an axle which has been lowered by deflation or removal of a tire. Yet, if they are to give efficient and satisfactory service, they should be extensible to a height providing ample working lee-way between the ground, or floor, and an inflated tire arranged on the wheel rim. A real problem is involved, in that a jack with the needed contractibility, will not, ordinarily, be capable of extension to a desired height. And, in the usual constructions, the action has been very slow, consuming considerable time and energy in the act of gradual change from low to high or high to low elevation.

It is an object of the invention to provide so that jacks may be constructed with ability to be contracted to a few inches in height, say four or six, for example, and with ability to be extended to a height approximating three times their height when fully contracted. Another object is to increase the speed of gradual ascent or descent of jacks, and this with no increase, but rather with a decrease, in the energy required to operate, as compared with jacks of the present types. A feature of importance is that the rest, at the top of the jack, does not rotate, and thus may be once positioned with respect to the object which is to be engaged, and then requires no further attention as regards setting. Still another feature resides in a convenient and efficient ratchet mechanism for operating the jack in the act of its extension

or construction. It is, moreover, an important feature that the structure employed provides exceptional strength, and lifting capacity; and withal, has a compactness which is especially advantageous, as a measure of convenience in handling and storage.

These objects and results are attained by resorting to the telescoping screw principle, now common in jacks, but by developing that principle beyond what has been done successfully heretofore, to my knowledge.

According to the invention three screws, each of different diameter, are made to cooperate in the act of extending or contracting the jack, they working under the urge of an operating sleeve which is adapted to be rotated, clockwise or reverse, by successive horizontal back and forth movements of a ratchet handle. The large screw of the telescoping trio is slidably keyed to the operating sleeve to rotate with it, and is threaded into the top of a base-standard. The other two screws are keyed against rotation, with respect to the base standard, the small one being threaded into the top of the operating sleeve, and slidably keyed to the medium sized screw, which in turn is threaded into the large screw, and slidably keyed to the standard. If the large screw has left-hand threads, the small screw and the medium sized one will have right-hand threads, so that rotation clockwise of the operating sleeve will cause independent motion upward of each screw, producing, for each complete rotation of the sleeve, an aggregate rise at the top-rest of the jack equal to the sum of the screw pitches of the three screws. And, because there is sliding connection between the operating sleeve and the large screw; between the standard and the medium sized screw; and between the small and medium sized screw, the maximum height possible of attainment for the jack is approximately a little less than the sum of the lengths of the three screws. Also, the operative action of my improved jack is simple and efficient, and is made easy by providing so that only a minimum amount of friction exists between parts which have relative rotary motion.

It is intended that the patent shall cover,

by suitable expression in the appended claims, whatever features of patentable novelty exist in the invention disclosed.

In the accompanying drawings:

5 Figure 1 is an elevation of my improved jack fully contracted;

Figure 2 is an elevation showing the jack fully extended;

10 Figure 3 is a plan with a part broken away to illustrate the ratchet mechanism;

Figure 4 is an elevation, in medial section through the jack, as seen in Figure 1;

Figure 5 is an elevation, in medial section through the jack, as seen in Figure 2;

15 Figure 6 is a plan, in section on 6—6 of Figure 4; and

Figure 7 is a plan, in section on 7—7 of Figure 4.

Referring to the drawings the jack there seen comprises a relatively large and flat base 10, a tubular base-standard 12, and an operating sleeve 14 for operating the three telescoping screws 16, 18 and 20, the latter of which carries at its top the jack-rest 21.

20 Standard 12 has its upper end threaded internally, as at 22, to receive the large screw 16, and is provided with longitudinal keyways 24, extending from a point just below the threads 22, out through the base of the

25 jack but normally closed at the base by cover plate 25. A disk 26 fits nicely within the bore of the standard 12, to slide freely therein; and it has tongues 26' projecting into the keyways 24 in the standard to prevent rotation 30 of the disk with respect to the standard. Rising from this key-disk 26 is a hexagonal shank 28 which extends with sliding but not rotatable fit through a hexagonal hole 30 in the bottom 18' of the second-largest screw 18,

35 which screw is threaded into the upper end of the larger screw 16. The nut 28' on the end of shank 28 limits the upward movement of the screw 18 as when the key-disk 26 has been so far lifted that its tongues 26' have 40 reached the ends of the keyways 24.

The second-largest screw 18 is provided at its top with a circular table 32, and the operating sleeve 14 is rotatably supported on this table with suitable ball-bearings 34 intervening. It is maintained thereon by the pin-end 45 of screw 36 which underlies the rim of the table. Thus screw 18 and the operating sleeve 14 must move in unison in vertical directions, but the sleeve is free to rotate about the screw,

50 which is keyed to the base-standard. The large screw 16, however, is made to rotate with the sleeve, it having keys 16' on its head which slidably engage in longitudinal keyways 14' formed internally of the sleeve.

55 The third and smallest screw may be seen at 20, it being threaded into the top of the operating sleeve, as at 38, and extending into the hollow of screw 18, where it is slidably keyed to said screw as at 40, and held with 60 that screw against rotation. As illustrated,

the large screw 16 has left-hand threads, while the other two screws have right-hand threads. Thus, with the jack fully contracted, as seen in Figures 1 and 4, a clockwise rotation of sleeve 14 will cause the large screw 16 to move upward relative to the base and base-standard; will cause the second-largest screw 18 and the operating sleeve to move upward relative to the large screw; and will cause the small screw 20 to rise with respect to the second-largest screw. As a result of a complete rotation of the operative sleeve, the aggregate rise, at the jack-rest 21, will equal the sum of the pitches of the three screws. Thus, if the pitch of each screw is three sixteenths of an inch, which is a practical dimension, the total lift at the rest 21, occasioned by a single revolution of the operating sleeve, will be nine sixteenths of an inch, or considerably more than is operatively possible with jacks as heretofore constructed.

65 The means for rotating the operating sleeve 14, to extend or to contract the jack, is exceedingly simple, convenient and efficient. The action may be by short back-and-forth horizontal movements of a suitably long handle 42, which movements are transmitted to collar 44 which is rotatably mounted on the operating sleeve, and through ratchet 46 to the sleeve itself. For this purpose the sleeve has, near its upper end, a peripheral ring-portion 48 of considerably larger diameter than the main body of the sleeve, and the periphery of this ring-portion is provided with a multiplicity of squared notches 50 in which the ratchet 46 is adapted to engage to effect rotation of the sleeve. The ratchet is mounted 70 at the juncture of handle and collar, pivoted at 52, and, preferably, is of the double-acting type, with finger-pieces 54 extending out a little at each side in position to be flipped by the operator to bring one or the other of the ratchet-prongs 56 into notch-engaging position.

75 The spring-pressed pin 58, riding on the bevelled back faces of the ratchet, provides a snap action when the ratchet passes neutral position in the act of shifting it. Thus the mentioned back-and-forth movements of handle 42 will cause intermittent rotation of 80 the operating sleeve 14 in clockwise or anti-clockwise direction accordingly as one or the other of the ratchet-prongs 56 is in position to effect the said turning.

85 The manner of mounting the collar 44 on the ring-portion 48 of the operating sleeve provides a minimum of friction which results in an exceedingly easy operative action. To this end ball-bearings 59 are inserted between the upper surface of ring 48 and the top of 90 collar 44, they being arranged in a circle on said ring before the collar is slipped over the operating sleeve when assembling. A peripheral groove 60 is provided in the ring 48, under the notches 50 therein, and a like groove 95

100

105

110

115

120

125

130

62 is provided, on the collar, in the inner surface which lies adjacent to the first mentioned groove. Thus, when the collar 44 is in place on the ring 48, the two adjacent grooves 60, 5 62 form a circular hole around the ring, into which hole a multiplicity of ball-bearings 64 may be fed through the hole in the 66 on the collar. And then the hole may be closed by screw 68. Thus, both radial and axial thrust 10 at the collar 44 is provided for, and the lower circle of balls 64 serves the added function of maintaining the collar on the operating sleeve.

My improved jacket embodies several important advantages over the ordinary and usual constructions, and has capabilities whereby it fills an urgent need in the art to which the invention relates. In addition to its operative features of utility and novelty, 20 it has characters of sturdiness and compactness which render it particularly appealing to the trade.

I claim as my invention:

1. A jack comprising a standard, and three telescoping screws, the outer one of which is threaded into said standard, the middle one of which is threaded into the outer screw, and slidably keyed to said standard, and the inner one of which is slidably keyed to said 25 middle screw; and an operating sleeve for the screws threadedly engaging said inner screw, and slidably keyed to said outer screw; said outer screw having threads reverse of the other two screws, whereby rotation of said operating sleeve effects vertical movement of all of said screws, each with a different rate of travel from that of its neighboring screws, in the same direction relative to the said standard.

2. A jack comprising a standard; three telescoping screws; and means for operating all of the screws, each with a different rate of travel from that of its neighboring screws, in like vertical direction relative to said standard; one of said screws being threaded into said standard, and slidably keyed to said operating means, for rotation therewith; and the other two screws, having threads reverse to those of the first screw, being slidably keyed together, and one of them being slidably keyed to said standard, whereby they are held against rotation, and one of the latter said two screws being threaded into said first screw, and the other threadedly engaged by said operating means.

3. A jack comprising a standard; three screws; and means for operating all of the screws vertically and simultaneously in like direction but each with a different rate of travel from that of its neighboring screws, with respect to said standard; said screws being mounted each to travel into said standard in telescopic relation, and to travel out 65 of said standard with each screw supporting

the screw next within it, in extended relation.

4. A jack comprising a standard; three screws operable into and out from said standard, each with a different rate of travel from that of its neighboring screws, in like direction; and means for effecting said screw movements, comprising an operating sleeve keyed to one of said screws, rotatably supported on another said screw, and threadedly 70 engaged with the third said screw.

5. A jack comprising a standard; three telescopically arranged screws supported by said standard; and means for operating all of said screws, each with a different rate of travel from that of its neighboring screws, in like direction; said operating means comprising an element surrounding the screws and the standard, it being rotatably supported on the middle one of said screws, 80 slidably keyed to the outer screw, and in threaded engagement with the inner screw.

6. The combination of three telescopically arranged screws; a support; and means for simultaneously operating all three screws, each at a different rate of travel, in like direction; the outer one of said screws being threaded internally and externally with its exterior threadedly engaging said support; the middle screw being threaded into said 90 outer screw and slidably keyed to said support; the inner screw being slidably keyed within said middle screw; and said operating means comprising an element surrounding the screws and the support, it being rotatably secured to said middle screw, slidably keyed to the outer screw, and in threaded engagement with the inner screw.

7. A jack comprising a standard; three screws operable into and out from said 100 standard, each with a different rate of travel from that of its neighboring screws, in like direction; a rotatable operating sleeve supported on one of the screws and operatively connected to the other two screws; and horizontally arranged ratchet mechanism for rotating said sleeve.
